RIVETING MACHINE

Filed April 16, 1929

Inventor:

Howard Elsner

UNITED STATES PATENT OFFICE

HEINRICH ELSNER, OF DRESDEN, GERMANY

RIVETING MACHINE

Application filed April 16, 1929. Serial No. 355,612.

The present invention relates to riveting machines, and has for its object to facilitate the riveting process and render it more accurate.

The invention consists in providing two feeding devices for the rivets and in fitting the plunger with a double riveting set while the jaws are arranged jointly or separately on the rivet case which is slidingly connected with the set and is pressed against the latter by a spring. The case of the rivet comprises at least two parts arranged so that a lateral opening is provided and the rivet can be introduced on the side or at the lower end of the case. This arrangement affords the advantage that the jaws can grip the shank or stem of the rivet slightly below its head so that the shank remains visible underneath the jaws and it thus becomes possible to determine the exact spot where riveting is to take place, which is highly important especially when double riveting has to be resorted to.

One embodiment of the invention is illustrated in the accompanying drawings, in which Figure 1 is a front view of the plunger and feeding device; Fig. 2, a side view of the same; Fig. 3, an enlarged side view of the lower part of the plunger; and Fig. 4, a front view of the same.

Referring to the drawing, 1 are the rivets which are placed in the feed drums 2 and 3 whence they pass through the two rivet guides 4 and 5, provided with the separators 6 and 7, into the lower end of the rivet case 7'. The plunger 8 is provided at its lower part with a double set 9 and 10 which cooperates with the dollies 11 and 12. The case 7' is arranged directly on the set or plunger 8 and adapted to slide thereon. The spring 13 tends to press the case 7' constantly against the plunger 8, i. e., to pull it up, the upward movement being limited by a stop 14. The case 7' carries jointly or separately the pairs of jaws 15 and 16 which are adapted to swing about the bolt 17 either separately or may be made of one piece. Owing to the action of the springs 18 and 19 they are continually pressed against the plunger 8 which they hug with their noses 20. The case 7 consists of

at least two parts having a lateral opening 21 to permit the introduction of the rivet laterally as well as at the lower end of the case. The rivet 1 will then project downwardly with its shank and be gripped by the jaws slightly below the head. As the shanks of the rivets project, the exact spot where the riveting process is to take place can be ascertained accurately.

I claim:—

A riveting machine comprising two rivet feeding devices, a plunger formed with a double riveting set, a rivet case arranged directly on the said plunger and adapted to slide thereon, a spring to pull up the said riveting case on the said plunger, pairs of jaws adapted to swing about bolts on the said case, and springs to draw the jaws against the said plunger, the jaws being arranged to grip the rivets slightly below their heads.

In testimony whereof I have affixed my signature.

HEINRICH ELSNER.
